CONTAINER FOR FRAGILE ARTICLES

George L. Richmond, Newark, N. Y., assignor to
Bloomer Bros. Company, Newark, N. Y., a cor-
poration of New York

Application May 12, 1933, Serial No. 670,757

4 Claims. (Cl. 217—34)

This invention relates to containers for fragile articles such as eggs or the like.

An object of the invention is to provide a generally improved and more satisfactory container 5 of this character, and especially one which can be manufactured at slight expense and yet which will give adequate cushioning support to eggs or other fragile articles so that the possibility of breakage in handling is greatly reduced.

10 Another object is the provision of such a container so designed and constructed that it may be erected into normal operative condition or collapsed substantially into flat condition.

15 A further object is the provision of such a container so designed and constructed that it may be readily manufactured by existing machinery without the necessity of making expensive changes in standard carton making machines.

20 To these and other ends the invention resides in certain improvements and combinations of parts, all as will be hereinafter more fully described, the novel features being pointed out in the claims at the end of the specification.

25 In the drawing:

Fig. 1 is a plan of a carton constructed in accordance with the preferred embodiment of the invention, showing it in erected position with the cover thrown back to illustrate the interior construction;

30 Fig. 2 is a vertical section taken longitudinally through the structure of Fig. 1;

Fig. 3 is a vertical section taken transversely through the structure of Fig. 1;

35 Fig. 4 is an elevation of one of the transverse partitions used in the filler;

Fig. 5 is an elevation of the cushioning or support member used in the filler, detached from the other parts, and

40 Fig. 6 is an elevation of a fragment of the filler in collapsed position.

The same reference numerals throughout the several views indicate the same parts.

45 The carton of the present invention is intended primarily for holding eggs, although it is to be understood that it is applicable also to holding other fragile articles such, for example, as electric light bulbs, Christmas tree ornaments, and the like.

50 According to the present invention there is provided a two-part construction embodying a body capable of being collapsed into substantially flat form or erected to form a hollow structure, and a filler placeable in the body when the latter is erected, this filler also being collapsible

into substantially flat form when it is removed from the body.

5 The body may be of any suitable known construction, made usually of cardboard or the like so formed as to provide a front wall 10, a bottom 11, a rear wall 12, end walls 13, a cover 14, and a cover flap 15 adapted to be thrust downwardly just inside the front wall 10 when the box is closed. This box body may be collapsed in any suitable known manner.

10 When the body is erected to its normal operative position, an erected filler may be placed in it, which filler preferably comprises a plurality of longitudinal partitions and a plurality of transverse partitions capable of being collapsed 15 (when the filler is removed from the body) by swinging the partitions relatively to each other about their intersections in known manner. The shape and size of the body may be varied as desired, and any desired number of partitions may be employed to make any desired number, size, or shape of compartments.

20 In the preferred embodiment, the carton is intended to hold a dozen eggs arranged in two rows of six eggs each, and consequently the filler is 25 preferably made up of three longitudinal partitions 21, 22, and 23 and seven transverse partitions each indicated by the numeral 25. It will be noted that, as well understood by those skilled in the art, the longitudinal partitions 21, 22, and 23 occupy when in normal position substantially vertical planes which are arranged substantially parallel to each other, and the transverse partitions 25 likewise occupy substantially vertical parallel planes extending transversely to and intersecting the planes of the longitudinal partitions.

30 The partitions are slotted in any suitable known manner at their intersections so that they may 35 extend through each other. That is, for example, the transverse partitions 25, as shown in Fig. 4, may have vertical slots 28 extending from their bottoms approximately half way up toward their tops, through which the lower parts of the longitudinal partitions extend, and the longitudinal partitions may have slots extending downwardly approximately half way from their upper edges, in the planes of the transverse partitions, through which the upper parts of the transverse 40 partitions may extend. The slots in the longitudinal partitions may also be provided at one edge with locking lugs 29 (Fig. 6) adapted to engage in known manner in holes 30 in the transverse partitions to lock the partitions to each other against accidental vertical displacement.

As well understood by those skilled in the art, the filler structure when removed from the box body may be collapsed into substantially flat condition by swinging the longitudinal and transverse partitions relative to each other about their intersections.

According to the present invention, novel and improved supporting and cushioning means is provided for holding the eggs or other fragile articles. This cushioning means comprises a piece of suitable sheet material (which may be of cardboard similar to that from which the partitions are formed) set edgewise substantially in the center of each compartment and presenting an upper edge on which the fragile article in that compartment may rest. Preferably also this upper edge is shaped to conform at least approximately to the shape of the contacting part of the fragile article.

In the preferred embodiment, the cushioning and supporting means is formed by two strips of material 35, one extending longitudinally of the filler substantially parallel to and substantially midway between the longitudinal partitions 21 and 22, and the other cushioning member 35 being similarly located between the longitudinal partitions 22 and 23.

As will be readily apparent from the drawing, these cushioning members 35 extend substantially vertical and are thus presented edgewise to the fragile articles placed in the compartments between the intersections of the various partitions, so that the fragile articles rest upon the thin upper edges of the members 35 and are cushioned thereby and held from direct contact with the bottom 11 of the body.

In order to accommodate the cushioning and supporting members 35, the transverse partitions 25 are provided with slots 37 extending upwardly from their bottom edges for a sufficient distance, approximately midway between the slots 28, and the members 35 have downwardly extending slots 38 in the planes of the transverse partitions. Likewise the member 35 may have at one edge of each slot 38 a locking lug 39 similar to the locking lugs 29 of the longitudinal partitions, for engagement with the bottom edge of a hole 40 appropriately placed in each transverse partition 25, to lock the transverse partitions and the cushioning member against vertical displacement relatively to each other.

Preferably also the upper edge of the member 35 is shaped to conform at least approximately to the contacting part of the fragile article which is intended to rest on the member 35. When the construction is intended for use with eggs, as in the preferred embodiment, the upper edge of each member 35 may be scalloped or hollowed out between each two transverse partitions as indicated in general at 45, to conform approximately to the shape of one end of an egg.

It will be seen that the members 35 are not as high as the partitions, so that their upper edges are materially below the tops of the compartments formed between the intersections of the various partitions. Thus a fragile article, such as the egg indicated by the dotted lines 50 in Fig. 2, may be placed within a compartment and will rest on the upper edge of the cushioning member 35 within that compartment and be cushioned and supported thereby and held up out of contact with the bottom 11 of the carton.

The cardboard or similar sheet material from which the cushioning and supporting members are made has sufficient give and resiliency even

in an edgewise direction, so that a noticeable cushioning effect is secured, and the fragile articles are held with greater security than if they rested directly on the flat bottom 11 of the carton. Furthermore, the use of this cushioning member obviates the necessity for the placing of a packing pad beneath the carton when the eggs are being dropped into the compartments.

Since the members 35 are arranged in planes parallel to the longitudinal partitions 21, 22, and 23, it follows that they will not interfere in any way with the collapsing of the filler but will simply be collapsed between the longitudinal partitions when the transverse partitions are swung around their vertical intersections with the longitudinal partitions and with the members 35. The filler when in a collapsed condition may be easily erected in exactly the same way that the conventional and heretofore known filler is erected, and it is not necessary to pay any special attention whatever to the cushioning member. It is automatically placed in proper position when the filler is erected and it needs no further movement or attention of any kind.

I claim:

1. A container for fragile articles comprising a plurality of longitudinal partitions lying substantially in spaced parallel planes when in normal erected position, a series of transverse partitions normally extending across said longitudinal partitions to subdivide the space between them into a plurality of separate compartments for receiving fragile articles, said longitudinal and transverse partitions being hinged to each other at their intersections and capable of being collapsed from said normal positions into substantially flat condition, and a supporting member of sheet material lying when in normal erected position substantially in a plane parallel to and midway between said spaced parallel planes and presenting an edge on which fragile articles placed in said compartments may rest, said supporting member intersecting said transverse partitions and being hinged thereto about axes substantially parallel to those of the hinge connections between said longitudinal and transverse partitions, so that said supporting member may maintain its position substantially parallel to said longitudinal partitions during collapsing and erecting movements of said partitions.

2. A container for fragile articles comprising a plurality of longitudinal partitions lying substantially in spaced parallel planes when in normal erected position, a series of transverse partitions normally extending across said longitudinal partitions to subdivide the space between them into a plurality of separate compartments for receiving fragile articles, and a supporting member of sheet material lying when in normal erected position substantially in a plane parallel to and midway between said spaced parallel planes, said supporting member presenting a thin upper edge on which fragile articles placed in said compartments may rest, and said upper edge being shaped to conform approximately to the shapes of the contacting parts of the fragile articles intended to be placed in said compartments.

3. A container for fragile articles comprising a body of sheet material collapsible substantially into a flat condition and erectable into a hollow structure, and a filler placeable in and removable from said body when it is erected, said filler embodying a plurality of longitudinal partitions in substantially vertical planes and a plurality of transverse partitions in substantially vertical

planes intersecting the planes of the longitudinal partitions and a cushioning member in a substantially vertical plane substantially parallel to certain of said partitions and intersecting others of said partitions, said filler when erected having compartments between said partitions in which fragile articles may be placed to rest loosely upon the upper edge of said cushioning member and to be held against lateral displacement by contact with the adjacent partitions on either side of the cushioning member on which the article rests, and said filler being collapsible into substantially flat form by swinging said longitudinal and transverse partitions relatively to each other about their intersections.

4. A container for fragile articles comprising

spaced substantially parallel upstanding walls forming sides of a compartment for holding a fragile article, and a cushioning member of sheet material placed on edge substantially midway between and parallel to said walls, said cushioning member having an upper edge shaped approximately to the shape of a portion of the surface of a fragile article to be placed in said compartment, to form a seat on which said fragile article may rest, said upstanding walls extending upwardly to elevations materially above said seat and serving as lateral supports for said fragile article to prevent displacement of said article from its seat in a direction laterally of said cushioning member.
